PORTABLE CONCRETE STEP

Henry A. Byington, Adel, Ga.

Application June 15, 1938, Serial No. 213,907

11 Claims. (Cl. 72—96)

My invention relates to a stair construction.

An object of my invention is to provide a light, portable stair construction of separable sections.

A further object is to provide a construction of premolded concrete parts which can be assembled on the job.

Another object is a separable unit molded stair construction having novel interlocking stringers and risers arranged so that the tread members are entirely relieved of stress other than those of live loads.

Still another object is to provide a novel stair assembly, the parts of which when assembled, firmly interlock to form a rigid construction without the use of auxiliary binding or connecting elements.

In the drawings:

Figure 1 is a perspective view of one embodiment of my invention.

Figure 2 is a perspective view of one of the riser seats in a stringer.

Figure 3 is a perspective view of an interlocking riser end for fitting into the seat of Figure 2.

Figure 4 is a section on line 4—4 of Figure 3.

Figure 5 is a perspective view showing an alternative construction of stringer.

Figure 6 is a view of a stringer similar to that shown in Figure 1, but having a modified riser seat.

Figure 7 is a view of the riser used with the stringer of Figure 6.

Figure 8 is a perspective view of a stair tread used in my assembly.

Figure 9 is a perspective view of a further alternative embodiment of stringer construction.

Figure 10 is a perspective view of an intermediate riser for use with the stringer construction of Figure 9.

Figure 11 is a perspective view of one of the end risers used with the stringer of Figure 9.

In the attached drawings forming a part of this specification and in which like numbers have been used to designate like parts throughout the same, the numeral 10 designates my preferred form of molded stringer which may be reinforced by welded wire fabric 11. On the upper edge of these stringers are formed flat step-supporting surfaces 12 connected by curved surfaces 13. Formed in the sides of the stringers 10 at each flat surface 12 thereof, are riser receiving channels 14 being of a width equal to the length of each of said surfaces 12. These channels will be vertical when the stair is set up

ready for use. These channels 14 are of two depths, the deeper portion being indicated by 15, and a shallower portion by the numeral 16. In the bottoms of both channel portions 15, 16, are inwardly and downwardly curved sockets 17 for a purpose to be later described.

I will now describe my novel riser designated by the numeral 18. These risers may be of molded concrete construction re-inforced by welded wire fabric 11 similar to that used in the stringers 10. The risers 18 have a rearwardly right angled extending portion 19 extending the length of their top edges, and of a width equal to that of the shallow stringer channel 16. Formed at each end of the portions 19 are bosses 20 similar to bosses 21 formed adjacent the lower corners of the risers. These bosses are of such shape and so spaced as to neatly fit into the upper and lower stringer sockets 17 with the riser top flush with the horizontal stringer surfaces 12. 20 This boss socket arrangement forms a positive lock against any twisting or rocking of the assembly when set up. As illustrated in Figures 1 and 4, a longitudinal rib 22 is formed on the front side of risers 18 for supporting the rear edge of a step-tread 23. Each step 23, illustrated in Figure 8, has projections 24 at its front corner for extending over the flat step portions 12 of the stringers. Formed on the under surface of each tread is a rectangular projection 25 of such dimensions as to fit snugly between the rear edge of a riser portion 19 and front edge of rib 22, as shown in Figure 1.

In Figure 5 is illustrated an alternative form of stringer 26. This stringer has riser receiving channels and sockets similar to those shown in stringer 10, but has an integral buttress 27 extending along its outer edge. The step-treads used with this form of the invention are similar to that shown in Figure 8, except that the projections 24 will be shorter so as to abut the inner side of stringer buttress 27.

A third embodiment of my invention is illustrated in Figures 6 and 7. In this form, the stringer 28 is similar to the stringer 10 of Figure 1 except that it is provided with single depth channels 29 having sockets 30 for receiving bosses 31 of a single width riser 32 (Figure 7). This riser has a tread supporting rib 22 similar to that of the riser 18 previously described.

The alternative embodiment of the invention shown in Figures 9, 10 and 11 comprehends a stringer 33 similar to the stringer 28 of Figure 6, except that its intermediate riser channels 34 have parallel straight side walls and straight 55

ends with flat bottoms 35 perpendicular to the walls and ends.

In this embodiment the top and bottom end riser channels 36 and 37, respectively, are of substantially dovetailed form with at least one side wall thereof dovetailed, and their bottoms being flat.

The intermediate risers used in this embodiment are as shown in Figure 10, each comprising a monolithic block 38 shaped at each end to conform to the riser channels 34, and having a laterally enlarged base portion provided with a flat front shoulder 40 as a tread seating ledge. The length of the base portion is such that it abuts the stringers at each end.

The top and bottom risers used in this embodiment are identical, each consisting of a monolithic block 38' identical to the intermediate riser 38 of Figure 10 except that its ends 41 are dovetailed to conform to the stringer channels 36 or 37. The riser is formed with a base portion 39' and shoulder 40' identical to the base and shoulder of an intermediate riser.

In all embodiments of the invention the interlocking of the structure is accomplished in the risers and stringers and without imparting to the treads any stresses other than those incident to the live loads occurring in service. The stringers are anchored against inclination toward or away from each other by the risers, which bear the least load of any sections of the structure and are thus enabled to function at maximum efficiency with respect to durability and resistance to stress.

From the above description it can be seen that I have provided a light and portable step construction with practically the same capacity, stability and rigidness as one cast in a single unit.

It is to be understood that the forms of my invention herewith shown and described are to be taken as preferred embodiments, and that changes in shape, size and arrangement of parts may be resorted to without departing from the spirit of the invention or the scope of the claims.

I claim:

1. In a stair construction, stringers having channels formed in their inner sides, said channels having sockets in their bottoms, risers having bosses formed at their ends for fitting into the channel sockets, and step treads for extending between the stringers.

2. In a stair construction, stringers having channels formed in their inner sides, said channels having sockets in their bottoms, risers having bosses formed at their ends for fitting in the channel sockets, projections on the front face of the risers, and step treads supported by the risers and said projections.

3. In a stair construction, stringers having channels formed in their inner sides, the channels having sockets formed in their bottoms, risers having bosses formed at their ends for fitting into said sockets, a longitudinal rib on the front face of each riser, and step treads having their front edges supported by a riser and their rear edges by the longitudinal ribs.

4. In a stair construction, stringers having channels formed in their inner sides, upper and lower sockets formed in the said channels, risers having upper and lower bosses at their ends for seating in the channel sockets, a horizontal support formed on the front side of the risers, and step treads supported by the risers and horizontal supports.

5. In a portable molded stair construction, stringers having stepped portions on their upper edges, the said stepped portions being connected by curved surfaces, vertical channels formed in the inner sides of the stringers adjacent each stepped portion, the channels having their bottoms situated at different levels and having sockets formed in each bottom, risers having right-angled flanges at their upper edges, bosses formed on the lower corner of each right angled flange and lower riser edge for fitting into the channel sockets, and a tread carried by the stringers and risers.

6. In a separable molded stair construction, stringers having integral buttresses formed along their upper and outer edges, vertical channels formed in the inner sides of said stringers, the said channels extending into the stringers to the inner edges of the buttress, the said channels having their bottoms formed at different levels, sockets formed in the bottom of each channel level, risers having rearwardly extending angled portions at their top edges, bosses formed on the lower corners of the angled portions and adjacent the lower corners of the risers for fitting into the stringer channel sockets, a horizontal projection formed on the front face of each riser, and step treads supported at their front edges by a riser top and at their back edges by a horizontal projection, the said treads having a depending portion on their bottoms for fitting between the back edge of a riser angled portion and the following riser horizontal porjection.

7. In a separable molded stair construction, stringers having stepped portions on their upper edges and having curved surfaces connecting the said stepped portions, channels formed in the inner sides of the stringers and extending downwards from each flat surface, a socket formed in the bottom of each channel, risers having bosses formed in their ends adjacent each lower corner for fitting into the channel sockets, a longitudinal rib formed on the front face of each riser, and step treads carried at their front edges by the stringers and riser top and at their rear edges by a horizontal rib and having depending portions fitting between the back edge of a riser and the front surface of the longitudinal rib.

8. In a separable molded stair construction, stringers having stepped surfaces on their upper edges, the stepped portions being connected by curved surfaces, channels extending downwards from each stepped surface in the inner sides of the stringers, each channel having its bottom formed at different vertical levels and having sockets formed therein, risers having rearward extending portions at their upper edges, downward extending bosses formed under the corner of each rearward extending portion in each riser end adjacent its lower corners for fitting into the stringer channel sockets, a longitudinal rib formed on the front surface of each riser, and a step tread having extensions at each front corner for resting on the stringer stepped surfaces, and having a depending portion on its under side for fitting between the back edge of the riser angled portion and front surface of the longitudinal rib of the following riser.

9. A sectional stair construction comprising stringers having riser end receiving channels in their opposed side faces, risers detachably seated at their ends in said channels, certain of said risers being interlocked with said stringers to pre-

vent movement thereof longitudinally of the risers, and tread sections detachably seated on said stringers and risers and free of interlocking engagement with either.

- 5 10. A sectional stair construction comprising stringers having riser end receiving channels in their opposed side faces, risers detachably seated at their ends in said channels, tread supporting portions on said risers, tread sections detachably
10 seated on said stringers and risers, and certain of

said risers having interlocking engagement at their ends with the stringers.

11. In a sectional stair construction, stringers having channels in their inner side faces only, risers detachably seated at their ends in said channels and interlocking therewith to prevent movement of said stringers in any direction longitudinally of the risers, and tread sections having free end seated engagement on the stringers.

HENRY A. BYINGTON. 10
